Primary Examiner — Nathan M Johnston

(74) Attorney, Agent, or Firm — Frost Brown Todd LLC

(57) **CLAIM**

The ornamental design for a dispenser, as shown and described.

DESCRIPTION

FIG. 1 is a front right perspective view of a dispenser, showing our new design;

FIG. 2 is a front left perspective view of the dispenser of FIG. 1;

FIG. 3 is a front elevational view of the dispenser of FIG. 1;

FIG. 4 is a rear elevational view of the dispenser of FIG. 1;

FIG. 5 is a right elevational view of the dispenser of FIG. 1;

FIG. 6 is a left elevational view of the dispenser of FIG. 1;

FIG. 7 is a top plan view of the dispenser of FIG. 1; and,

FIG. 8 is a bottom plan view of the dispenser of FIG. 1.

The broken lines shown in the drawings represent features of

the dispenser that form no part of the claimed design.
